UNITED STATES PATENT OFFICE.

GEORGE G. KITZEMAN, OF DES MOINES, IOWA.

POCKET-BILLIARD RACK AND OPERATING MECHANISM THEREFOR.

1,246,436.

Specification of Letters Patent.

Patented Nov. 13, 1917.

Application filed October 18, 1916. Serial No. 126,447.

To all whom it may concern:

Be it known that I, GEORGE G. KITZEMAN, a citizen of the United States, and resident of Des Moines, in the county of Polk and State of Iowa, have invented a certain new and useful Pocket-Billiard Rack and Operating Mechanism Therefor, of which the following is a specification.

The object of my invention is to provide a pocket billiard rack and operating mechanism therefor for use on pocket billiard tables, to be used in connection with other mechanism which may be coin operated or not, as desired, for measuring, recording and indicating the games played on the table.

A further object is to provide such a device including a collapsible triangle or rack, with means for mounting the said rack on a table, so constructed and arranged that in one of its positions the collapsible rack stands out of the way of players, and in another position the rack will move to position above the table for receiving and racking the balls.

A further object is to provide means for operating the rack, so constructed and arranged that the movements of the rack are positive and accurate.

Still a further object is to provide such mechanism having means for holding the rack in its collapsed position.

Still a further object is to provide in such a device a variety of cushioning means for taking the shocks of the movements of the parts in swinging the rack from its inoperative to its operative position.

A further object is to provide a device of this kind having an extensible arm or triangle supporting mechanism, with yielding devices for normally holding said arm in collapsed position when the rack or triangle is moved from operative position to inoperative position off the table.

Still a further object is to provide such a device adapted to be used with a coin or otherwise controlled mechanism for numbering and recording games and players, such as that disclosed in my Patent Number 1,114,148, issued October 20, 1914.

It is also my object to provide a device including a suitable spring mechanism adapted to swing the rack from inoperative to operative position when properly released by the coin or otherwise actuated

mechanism for numbering and recording games.

In this connection I may mention that this application is made in part to cover matter which I was required to divide out of the application on my said former patent.

My invention consists in the construction, arrangement and combination of the various parts of the device whereby the objects contemplated are attained, as hereinafter more fully set forth, pointed out in my claims and illustrated in the accompanying drawings, in which:

Figure 1 shows a vertical, sectional view through a portion of a billiard table with my improved pocket billiard rack and operating mechanism therefor mounted thereon.

Fig. 2 shows a vertical, central, sectional view of part of the operating mechanism shown in Fig. 1.

Fig. 3 is a side elevation of a central portion of the billiard table showing the billiard ball rack and operating mechanism in their inoperative position.

Fig. 4 shows a side elevation of a portion of a table, the rack operating mechanism and rack being shown in the position shown in Fig. 1.

Fig. 5 shows a vertical, sectional view of a portion of the table, the rack and operating mechanism being shown in their position midway between operative and inoperative position, part of the rack operating mechanism being shown in section, illustrating the operation of the parts, and

Fig. 6 shows a side elevation of a portion of a table with the rack mechanism in raised position just before the collapsing of the rack.

In the accompanying drawings I have used the reference numeral 10 to indicate generally a rail of a billiard table 11.

Mounted on the end of the billiard table 11 is a box or casing 12 having a coin or other actuated device for numbering and recording games, which may be like that described in my former patent, hereinbefore referred to.

Rotatably mounted in the walls of the casing 12, parallel with the side or the end of the billiard table 11 is a shaft 13. Fixed to the shaft 13 is a powerful coil spring 14, one end of which is fixed to the casing 12. The spring 14 normally holds the shaft 13 yieldingly in position for holding the

triangle or rack, hereinafter described, above the table 11.

On the shaft 13 within the casing 12 is a collar 15 from which extends an arm 16 adapted to coact with the spring catch 17, similar to the parts shown in my prior patent.

It will, of course, be understood that other means for connecting the shaft 13 with the mechanism for numbering and recording the games may be employed.

Secured to the billiard table adjacent to what may be called the outer end of the shaft 13 is an angle iron bracket 18, having an upwardly extending flange 19.

Resting adjacent to the flange 19 is a plate 20, adjustably mounted on said flange 19 by means of screws 21 screwed into the flange 19 and extended through vertically, elongated slots 22 in the plate 20.

On the upper portion of the plate 20 is a bearing 23 in which the shaft 13 is rotatably mounted.

The bearing 23 has at its upper portion on its ends shoulders 24.

Fixed on the shaft 13 at the opposite ends of the bearing 23 are arms 25, which extend away from the shaft and converge toward each other and are connected at their outer ends by a plate 26. The arms 25 have shoulders 27, shown in Fig. 3, adapted to engage the shoulders 24 when the arms 25 move to their upwardly extending position.

The plate 26 forms the hinged member having spaced opposite bearings 28, having a pintle 29, shown in Fig. 4.

Mounted on the pintle 29 between the bearings 28 by means of spaced bearings 30 is a coacting hinged member or plate 31, shown in Figs. 1, 3 and 4, having central, channel-shaped extensions 32 and 33 for supporting a tube 34 forming part of the telescoping rack supporting arm.

At the opposite ends of the extensions 32 and 33 are broken rings 35 and 36, having at their ends opposite flanges 37 and 38 adapted to be gripped together by means of bolts 39 and 40 for frictionally gripping the tube 34.

In what I shall call the inner end of the tube 34 is mounted a screw plug 41.

Extended into the tube 34 from the other end thereof and telescopically slidable in said tube 34 is a second tube 42 forming a part of said telescoping arm.

In the inner end of the tube 32 is a screw plug 43. Screwed into the wall of the tube 32 is a screw 44, the edge of which projects into a longitudinally, elongated slot 45 in the wall of the tube 34.

The ends of the slot 45 limit the sliding movement of the tube 32 with relation to the tube 34.

Received in the tube 34 between the plugs

41 and 43 is an extensible coil spring 46. Slidably extended into the outer end of the tube 42 is a slightly smaller tube 47, in the inner end of which is a screw-plug 48. A screw 49 is screwed into the wall of the tube 47 and has a head extended into the longitudinally elongated slot 50 in the wall of the tube 42. The ends of the slot 50 limit the sliding movement of the tube 47 with relation to the tube 42.

Received within the tube 42 between the plugs 48 and 43 is an extensible coil spring 51.

Slidably received in the outer end of the tube 47 is a similar tube 52, having in its inner end a screw plug 53. A screw 54 is screwed into the wall of the tube 52 and has a head slidably received in a longitudinally elongated slot 55^a in the wall of the tube 47. The ends of the slot 55^a limit the sliding movement of the tube 52.

An extensible coil spring 56^a is received in the tube 47 between the plugs 53 and 48. It will be noted that the screws 44, 49, and 54 prevent rotation of the tubes with relation to each other.

At the outer end of the tube 52 is a collapsible triangle or rack having the sides 55 and 56, hinged together at 57.

The third side 58 of the triangle is made in two parts hinged together at 59, as shown in Fig. 6. The ends of the members of the side 58 are hinged to the sides 56 and 55 at 60 and 61.

Secured to the side 56 of the triangle, adjacent to the hinge 50 is a spring 62, which is also secured to the side 58 and is designed to yieldingly, normally hold the triangle in its extended position. (See Figs. 3 and 6.)

Secured to the side 55 is a laterally, outwardly extending arm 63 which is designed to engage the side 58 at the end thereof opposite the spring 62 for limiting the opening movement of the triangle.

When the triangle is collapsed, by folding the side 58 inwardly, and folding the side 55 toward the side 56, as shown by dotted lines in Fig. 6, the collapsing movement is made against the action of the spring 62.

Mounted on the bolt 40 between the flanges 38 is a short plate 64 having in its outer end an opening 65.

Extended through the opening 65 is a chain 66. I preferably mount on the chain 66 a coil spring 67, so that part of said spring is on one side of the plate 64 and part on the other side thereof.

The ends of the chain 66 are secured to collars 68 on the shaft 13 on opposite sides of the arms 25.

The chain 66 is so arranged that it is slack, as shown in Figs. 3 and 5, at all times, excepting when the telescoping, rack supporting arm is arranged horizontally above

the table, and is so arranged that when said arm is in horizontal position above the table, as shown in Fig. 1, the chain is tight and serves to limit the swinging movement of the telescoping rack supporting arm on its hinge, thereby preventing the breaking of the hinge formed by the plates 26 and 31 and pintle 29.

The coil spring 67 normally stands in horizontal position and when the rack carrying arm, comprising the tubes hereinbefore described, swings from the position shown in Fig. 3 to the position shown in Fig. 5, and thence to the position shown in Fig. 1, it will be seen that as the chain tightens, the resiliency of the spring 67 will tend to cushion the shock on the parts as the chain moves to taut position, and just before the shoulders 27 engage the shoulders 24. The coil spring 67 also holds the chain 66 on opposite sides of the tube 34, and prevents said chain from catching on the inner end of said tube.

An additional cushioning device will now be described.

It will be noted that the arms 25 are fixed to the shaft 13, and that when the shaft is rotated, the entire rack carrying mechanism rotates around the center of the shaft 13 until the arms 25 reach the position shown in Fig. 5, where they extend upwardly and slightly outwardly away from the table.

The telescoping arm, composed of the tubes, then swings on the hinge formed by the plates 26 and 31 to position shown in Fig. 1, where the telescoping arm rests above the table.

To cushion the movement of the arm on the hinge last mentioned, I provide the following means:

Secured to the plate 26 on the side thereof adjacent to the table, when said plate is in the position shown in Fig. 1, is a bar 69 which is substantially horizontal when said plate is in said position. At the ends of the bar 69 are portions 70, bent from the bar 69 to position above and near the transverse center of said bar, and extending upwardly from the adjacent ends of said portion 70 are spring arms 71 spaced from each other and inclined from each other at their upper ends.

The device just described is shown in another position in Fig. 3.

The bar 69 is secured to the plate 26 by means of a flange 72, shown in Fig. 5.

Extended through openings in the members 70 are screws 73, which are screwed into the bar 69. The openings in the members 70 are large enough to allow said members some play with relation to the bar 69. The device just described is of resilient material.

Extending downwardly from the member 32, where said member joins the plate 31 is

a lug or an ear 74, so positioned that when 65 the arms 25 are swung upwardly to their position shown in Fig. 5, and the telescoping rack supporting arm is then swung downwardly over the table to the position shown in Fig. 1, the lug or ear 74 will move to 70 position between the members 71. The members 71 are close enough together, and the lug or ear 74 is so thick that it yieldingly forces the members 71 apart in order to permit the rack supporting arm to move 75 to its horizontal position over the table.

The portions 70 will also spring with relation to the plate 69 so as to further cushion the parts as the rack supporting arm moves to its horizontal position above the 80 table.

The cushioning device just described, also serves to hold the rack holding arm against swinging sidewise when it is above the table.

Suitably mounted, preferably near the 85 plate 26 between the pintle 29 and the shaft 13, is a pintle 75. Pivotaly mounted on the pintle 75 are spaced arms 76, which, when the parts are in the position shown in Fig. 1, extend upwardly on opposite sides 90 of the tube 34 and toward the outer end thereof, as shown in Fig. 1. Above the tube 34, the arms 76 converge toward each other and are formed on or connected with a plate 77, having near its free end spaced elongated 95 slots 78.

Extended through the slots 78 are screws 79 which are screwed into an extension 80 on a plate 81. The plate 81 has a pair of parallel, spaced arms or flanges 82, which 100 extend downwardly when the parts are in the position shown in Fig. 1, as shown. The plate 81 has its free end farthest from the plate 77 a downwardly extending arm 83.

Pivotaly mounted on the bolt 39 is a link 105 84, shown in Fig. 1, which, when the parts are in the position shown in said figure, extends upwardly and is pivoted at its upper end to the plate 77.

When the rack holding arm is in its ex- 110 tended position from the table, as shown in Fig. 1, the device comprised of the plate 81 and the arms 82 and 83 which is a rack holding device extends to position shown in said figure.

When the device is moved toward its collapsed and inoperative position, the rack is first collapsed and the tubes 34, 42, 47 and 52 are telescopically collapsed, and the telescoping arm is then swung upwardly away 120 from the table on its hinged pintle 29.

On account of the fact that the hinged points of the arms 76 are between the pintle 29 and the shaft 13, it will be seen that as the rack holding arm is swung upwardly and 125 away from the table the arms 82 and 83 will move toward the collapsed rack or triangle, so that the arm 83 will overlap the

side 55 of the triangle, as shown in Fig. 5, and thereafter during the further movement of the parts to inoperative position will prevent any opening movement of the triangle.

5 The arms 82 at the same time overlap the triangle side 56, as shown in Fig. 5.

I have provided further means for holding the triangle after it has been collapsed in proper position to be engaged by the 10 arms 82 and 83 during the movement from its position above the table to its position shown in Fig. 5, which I will now describe.

The device, now being described, comprises a rectangular frame 84^a, which when 15 the parts are in the position shown in Fig. 1, extend from the member 32 substantially a horizontal position below and spaced from the tube 42.

Pivoted to the end of the frame 84^a far- 20 therest from the member 32 is a plate 85 which rests above the frame 84 and has at its side edges downwardly extending flanges 86 overlapping the side edges of the frame 84.

Fixed to the forward portion of the frame 25 84 are springs 87, which, when the parts are in the position shown in Fig. 1, extend upwardly and tend to yieldingly hold the plate 85 spaced above and away from the frame 84.

30 When the triangle is collapsed and the tubes forming the triangle holding arm are moved telescopically together, the collapsing triangle will slide upon the plate 85 and the plate 85 acting under the influence 35 of the spring 87 will yieldingly tend to press the triangle toward the triangle holding device having the arms 82 and 83.

After the triangle holding arm is swung upwardly to position, shown in Fig. 5, the 40 triangle will be constantly engaged by the plate 85.

The plate 85 and the frame on which it is supported perform an additional function.

When the device is moved from its ex- 45 tended toward its collapsed and inoperative position, the user will grasp and collapse the triangle and push it toward the tube 34 until the triangle engages the plate 85. One then ordinarily grasps the frame 84, and 50 the triangle is thereby saved from the strain of serving as a handle whereby the device may be saved.

For preventing movement of the rack carrying arm with relation to the arms 25 55 and plate 26, during the first part of the movement of the device, from the position shown in Fig. 3 to the position shown in Fig. 1, I have provided the following means:

Extending downwardly from the exten- 60 sion 33, when the parts are in the position shown in Fig. 1, is an ear 88, having extending through it an opening 89.

Mounted or formed on the plate 26 is a socket or the like 90 having opposite slots

91, so arranged that when the tube 34 is 65 moved from its position shown in Fig. 1, to the position shown in Fig. 5, on its hinge, the ear 88 enters said slots and moves to position where the opening 89 registers with the openings 91 in the socket 90. 70

Pivottally or hingedly connected with the plate 20 below the level of the shaft 13, is a locking pin 92 bent upwardly around the shaft 13, and then extended into the socket 90. The length of the locking pin 92 is 75 such that when the parts are in the position shown in Fig. 1, or in their position shown in Fig. 5, the end of the pin 92 does not reach to the slots 91, but when the parts are moved from their position shown in Fig. 5 toward their position shown in Fig. 3, the locking pin 92 will slide farther into the socket 90 and will enter the opening 89 in the ear 88 and rigidly lock the plate 26 and the rack carrying arm against any hinged 85 movement with relation to each other.

It therefore follows that when the parts are in their lowered and inoperative position, the rack and the rack carrying arm will be held in their downwardly hanging 90 position, and said rack and arm cannot be swung outwardly where they would be in the way of players using the table. Thus securely locked, the triangle cannot be functioned nor manipulated, except by the 95 proper means connected with the mechanism for compensating, recording, and registering.

I have largely described the practical operation of my machine in connection with 100 the foregoing description of its construction.

It may be said in further explanation of the working of my device, that when the device is not in use, it is swung downwardly 105 at the side or end of the table and below the rail in the position shown in Fig. 3, with the rack collapsed and held against the plate 85 and engaged by the arms 82 and 83, and with the locking pin received in the 110 opening 89 in the ear 88 for locking the rack carrying arm with relation to the plate 26.

When the parts are swung to their downward position, the arm 16 is engaged by the 115 spring catch 17, whereby the parts are locked in their inoperative position until the spring catch 17 is released by the action of the coin actuated mechanism or by manual operation or otherwise, whereupon the 120 spring 14 will rotate the shaft 13 for swinging the parts upwardly and over the table. During the first part of this upward movement, the rack carrying arm is held rigid with relation to the plate 26 by the locking 125 pin, hereinbefore referred to, and just before the parts reach the position shown in Fig. 5, the locking pin leaves the ear 88,

whereupon the momentum of the rack and its carrying arm will swing the rack over the table to position where the rack carrying arm is substantially horizontal.

5 As the parts move from the position shown in Fig. 5, toward position where they are just above the table, the arms 82 and 83 will move away from the triangle, and the spring 62 will move the triangle to its 10 expanded position.

The triangle will be held against movement beyond properly expanded position by means of the limiting device 63.

When the triangle is released by the holding device, the springs in the tubes of the triangle carrying arm will shove the tubes outwardly for expanding said arm and thereby moving the triangle to proper position above the table, when the triangle may 20 be used for racking the carom or pocket billiard balls.

After the balls have been racked, the triangle may be elevated and then collapsed and the parts moved to their inoperative 25 position.

It will be seen that in a device of this kind, the triangle is always ready for use with the proper table, and when the mechanism is actuated, the triangle will automatically move to proper position above 30 the table.

The importance of a mechanism of this kind may be more clearly emphasized when it is stated that the device is intended to be 35 used with a coin or otherwise actuated mechanism, so arranged that the triangle cannot be used for racking the balls for starting a new game until the proper means are employed for causing the spring catch

40 17 to be released, and a record of the operation is obtained by means of the recording device.

The advantages of such a mechanism are obvious and are to some extent set forth in 45 my prior patent, hereinbefore identified.

I realize that numerous changes may be made in the arrangement and construction of the parts of my improved device without departing from its essential features and 50 purposes, and it is my intention to cover by my present application, and the patent to be issued thereon, any modifications of structure or use of mechanical equivalents, which may be reasonably included within 55 the scope of my claims.

I claim as my invention:

1. In a device of the class described, designed for use with a checking and recording mechanism, a support designed to be 60 hingedly mounted on a table, a game element holding arm pivoted with relation to said support, a game element on said arm, the parts being arranged to swing from position with the game element hanging

downwardly at the side or end of the table 65 to position above the table, and means for locking said arm rigidly with relation to said support during part of the swinging movement of the device toward or from its inoperative position at the side or end of 70 the table.

2. In a device of the class described, designed for use with a game checking and recording mechanism, a rotatably mounted shaft, a support fixed thereto, a game element carrying arm hinged to said support, a receiving member on said support, a member on said arm adapted to enter said receiving member, having an opening, and a locking bar pivotally supported and adapted 75 to enter said receiving member and the opening in said last described member, for locking said arm against hinged movement 80 with relation to said support, during part of the swinging movement of said support 85 and arm, when said shaft is rotated.

3. In a device of the class described, a support designed to be hingedly mounted on a table, a telescoping arm hingedly mounted on said support, a game element carried by 90 said arm, and yielding means for holding said arm in its extended position.

4. In a device of the class described, a support designed to be hingedly mounted on a table or the like, a game-element-carrying 95 collapsible arm hingedly mounted on said support, a collapsible game element mounted on said arm, means tending to yieldingly hold said arm in its extended position, means for engaging and holding said game 100 element when said device is moved to one position of its movement, whereby the arm is held in its collapsed position.

5. In a device of the class described, a pivotally mounted collapsible arm, a collapsible game element supported on said arm, a movable engaging member adapted when said game element and arm are collapsed and are moved to a certain position 105 of the pivotal movement of said arm to engage said game element for holding the game element and arm in their collapsed 110 positions during the further movement of said arm on its pivot.

6. In a device of the class described, a rotatably mounted shaft, a support fixed thereto, a game element carrying arm hinged to said support, a collapsible game element on said arm, a member carried by 115 said support and pivoted thereto at a point spaced from the hinged line of said arm, means for operatively connecting said member with said arm, whereby when said game element is collapsed and said arm is swung on its hinge to a certain position, said member will engage and hold said game element. 120

7. In a device of the class described, a shaft mounted for limited rotation, a sup-

port secured thereto, a game element carrying arm hinged to said support, coacting devices for yieldingly limiting the hinged movement of said arm and said support in 5 one direction.

8. In a device of the class described, a shaft designed to be mounted on the side or end of a table for rotation, a support on said shaft, means for limiting the rotation of said 10 shaft when said support approaches the side or end of said table, above the shaft, an arm hinged to said support, and coacting, cushioning and limiting devices for limiting the swinging movement of the arm with relation 15 to the support, whereby when said support reaches its last above described position, said arm is permitted to move to position above the table.

9. In a device of the class described, a 20 pivotally mounted support, an arm hinged thereto between its ends, means for limiting the pivotal movement of said support, and a flexible device secured to said arm near one end thereof, adapted to limit the pivotal

movement of said arm with relation to said 25 support.

10. In a device of the class described, a triangle-carrying, collapsible arm, a collapsible triangle mounted thereon, a yieldingly mounted plate carried by one portion 30 of said arm, said plate being adapted to engage said triangle when the triangle and the arm are collapsed.

11. In a device of the class described, a triangle carrying collapsible arm, a collapsible triangle mounted thereon, a yieldably mounted plate carried by one portion 35 of said arm, said plate being adapted to engage said triangle when the triangle and the arm are collapsed, a pivotally mounted support, said arm being hinged on said support, and means for engaging said triangle 40 when the triangle and arm are collapsed and are moved to a certain position with relation to said support.

Des Moines, Iowa, October 12, 1916.

GEORGE G. KITZEMAN.
